(57) **CLAIM**

The ornamental design for a detailing stool, as shown and described.

DESCRIPTION

FIG. 1 is a front perspective view of a detailing stool showing my new design;

FIG. 2 is a rear perspective view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines in the figures are for the purpose of illustrating portions of the detailing stool, which form no part of the claimed design.
